R. A. NORQUIST,
COMBINATION HINGE AND LID SUPPORT.
APPLICATION FILED FEB. 17, 1921.

1,390,579.

Patented Sept. 13, 1921.

UNITED STATES PATENT OFFICE.

RALPH A. NORQUIST, OF JAMESTOWN, NEW YORK.

COMBINATION HINGE AND LID-SUPPORT.

1,390,579.

Specification of Letters Patent. Patented Sept. 13, 1921.

Application filed February 17, 1921. Serial No. 445,654.

To all whom it may concern:

Be it known that I, RALPH A. NORQUIST, a citizen of the United States, residing at the city of Jamestown, in the county of 5 Chautauqua and State of New York, have invented certain new and useful Improvements in Combination Hinge and Lid-Supports, of which the following, taken in connection with the accompanying drawings, is 10 a specification.

The invention relates to hinges for drop lids or hinged fronts for desks and similar articles; and the object of the improvement is to provide a combination hinge and support for a drop lid so that it shall be 15 strongly hinged and firmly supported at each rear corner of the lid with entire absence of construction which would be in the way or difficult of attachment or operation, yet hinging and holding the drop leaf or lid in the horizontal position for 20 table or desk use with a very strong support; and the invention consists in the novel features and combinations hereinafter set 25 forth and claimed.

In the drawings, Figure 1 is a perspective view of the drop front or lid support showing the preferred construction and arrangement of the same. Fig. 2 is a sectional view 30 of the front portion of the desk showing the left end of the drop lid in the raised or closed position, parts of the hinge showing in the correct position, the inner side of the pivot plate being shown as it would 35 naturally be attached to the corner post or desk side. Fig. 3 is a sectional view at line 3—3 in Fig. 1 with the hinge parts showing the leaf in the horizontal position; and Fig. 4 is an edgewise or top view of 40 the hinge parts in the open or horizontal position. Fig. 5 is a crosswise sectional view of the desk or case showing the two hinges on the drop front or lid, one at each rear corner of the same.

45 Like characters of reference refer to corresponding parts in the several views.

The numeral 10 designates the desk or case which has the drop lid or front 50 hingingly supported therein so that it can be dropped to and supported in the horizontal position shown in Fig. 5 and in dotted outline in Fig. 2, as a work table or desk.

The combination lid support and hinge 55 comprises the support bar 12 which has the attaching holes 13 therethrough, and the

pivot or hinge plate 14 which has the attaching holes 21 therethrough and the stop 15 near its inner end for the inner end 17 of the support bar 12. The support bar 12 60 is hingingly mounted on the pivot pin 16 on said pivot or hinge plate 14, the rear ends 17 of the support bars 12 extending back beneath the stops 15 to rigidly hold the lid 11 in the open or horizontal position, as shown in Fig. 5.

The stop 15 is preferably struck up by suitable dies from the pivot or hinge plate 14 so as to form a strong struck-out stop, which is called in the shop a blister, the 70 metal being upset and moved over at the lower edge so as to make a clean break against which the straight upper side of the end 17 squarely fits. The pivot pin 16 is a sufficient distance in front of the stop 75 15 to hold the lid 11 firmly in the extended or open horizontal position. The rear edge of the lid 11 is preferably arranged so as to form a tight joint 20 with the horizontal partition 18, a second partition 19 80 being arranged below the partition 18 so that when the lid 11 is in the closed position, it will close tightly upon the cross piece 22 thereby making a firm closure in either the open or closed position for said 85 rear edge 20 of the lid 11.

The plate 12 is preferably set into the rear portion of the edge of the lid 11 and fastened by suitable screws in the holes 13, and extends to said rear edge 20. The pivot or 90 hinge plate 14 is set into the post or side of the desk 10 so that said plate 14 and support bar 12 turn smoothly and flatly in line against one another, the rear surface of the edge 17 engaging squarely beneath the 95 struck-out stop 15.

It is now apparent that the drop lid 11 can be turned from the vertical position as shown in Figs. 1 and 2 to the horizontal position to thereby form a work table or 100 desk which is strongly supported, the leverage of the support bars 12 between the pivot pins 16 at each end of said work leaf or lid 11 holding with great strength against the under sides of the struck-out stops 15. It 105 is obvious that a pin or other construction of stop might be arranged on the plate 14 in the position shown, but the struck-out stop 15 is preferred because of its great strength and the ease and low cost at which it can 110 be struck out from said plate 14. It is preferably in the form of a semi-truncated cone

so that the entire stop has great strength and is able to support all that would ever necessarily be placed upon the lid 11. The rear edge 20 of the leaf 11 forms a close joint 5 with the partition 18 so that the two become a continuation of each other as a work table or desk. Pigeon holes or drawers may be arranged upon the partition 18.

What is claimed is:

- 10 1. In combination with a support, a plate rigidly attached to the support and having its upper free horizontal edge at the rear thereof struck outwardly and at a downward incline to form a rigid stop having a horizontal flat bottom which faces downwardly and a lid supporting bar pivoted to the plate between its ends and having a striking surface on its rear upper face engageable with the bottom of the stop.
- 15 2. In a combined hinge and lid support,
- 20 2. In a combined hinge and lid support,

a horizontal plate having means for rigidly securing to a frame, or the like and having a rigid stop struck-out therefrom, a bar having means for securing same at its front end to a lid, means to pivot the bar at a point between its ends to the plate and in front of the stop of the latter and a striking surface on the rear end of the bar beyond said pivot and on the upper face thereof to engage with and beneath the stop, the bar being movable to lie horizontal when engaged with the stop and at right angles to the plate in a second position.

In testimony whereof I have affixed my signature in the presence of two witnesses. 35

RALPH A. NORQUIST.
